Primary Examiner — Karen S Acker(74) *Attorney, Agent, or Firm* — Malloy & Malloy, P.L.(57) **CLAIM**

The ornamental design for a lenticular panel, as shown and described.

DESCRIPTION

FIG. 1 is a top right side perspective view of the first image of a lenticular panel according to my new design;

FIG. 2 is a top left side perspective view of the second image thereof;

FIG. 3 is a top plan view thereof;

FIG. 4 is a left side view thereof;

FIG. 5 is a front view thereof;

FIG. 6 is a right side view thereof;

FIG. 7 is a rear view thereof; and,

FIG. 8 is a bottom view thereof.

The broken lines in FIGS. 1 through 3 representing unclaimed graphical dolphin and sun shaped indicia form no part of the lenticular panel.
